UNITED STATES PATENT OFFICE

139,385

DESIGN FOR A CRANE CAB

John D. Rauch, Fort Wayne, Ind.

Application August 9, 1943, Serial No. 110,870

Term of patent 14 years

(Cl. D14—3)

To all whom it may concern:

Be it known that I, John D. Rauch, citizen of the United States, residing at Fort Wayne, in the county of Allen and State of Indiana, have invented a new, original, and ornamental Design for Crane Cab, of which the following is a specification, reference being had to the accompanying drawings, forming part thereof, wherein:

Figure 1 is a perspective view of a crane cab, showing my new design.

Figure 2 is a side elevational view looking toward one side of the crane cab.

Figure 3 is an elevational view of the side opposite that seen in Figure 2.

I claim:

The ornamental design for a crane cab, substantially as shown.

JOHN D. RAUCH.
